REFRIGERATING APPARATUS

Herbert C. Harvey, Camden, N. J.

Application October 6, 1934, Serial No. 747,135

7 Claims. (Cl. 62—127)

The principal objects of the present invention are: first, to improve and make more certain and reliable the control of the introduction of the high pressure refrigerant to the cooling coils, especially 5 when the latter are comparatively warm, as is the case in starting the refrigerating apparatus; to effect an economy in the utilization of the low pressure refrigerant for cooling the high pressure refrigerant, and generally to make refrigerating 10 apparatus more reliable and certain than it is at present.

Other objects of the present invention will appear from the following description at the end of which the invention will be claimed:

15 Generally stated the invention consists in the provision of a pressure responsive device for regulating the control valve for the high pressure refrigerant and acted upon by the occasional relatively high pressure of the low pressure refrigerant which occurs, for example, when the apparatus is started or is warm, in combination with a float for normally regulating the control valve for the high pressure refrigerant when the apparatus is in operation.

20 The invention also consists in the improvements to be presently described and finally claimed.

25 In the following description, reference will be made to the accompanying drawing forming part 30 hereof and in which—

The single figure is a transverse sectional view of apparatus embodying features of the invention.

In the drawing, 1 is the control valve that admits high pressure and comparatively warm refrigerants to the cooling coils or the like, which should be kept full of refrigerants. The high pressure refrigerant from the compressor enters by pipe 2, coil 3 and sieve or screen 3a and, after 35 passing the control valve 1, passes at reduced pressure by way of the connection 4 to the cooling coils. 5 is a chamber subdivided into a float chamber 6 and an accumulator chamber 7, and low pressure refrigerant from the coils enters it 40 at 8. From the accumulator chamber 7 there is a connection 9 back to the inlet of the compressor. 45 10 is a pressure responsive device, shown as a bellows 11 internally in communication with the atmosphere as by the vent 12, and externally in 50 communication with the accumulator chamber 7 as by vents 13. 14 is a float in the float chamber 6. 55 17 is a lever pivoted intermediate of its ends. At one end it is connected with the shank of the control valve 1 by a pivotal nut 18 and a lock-nut 19. The other end of the lever 17 is connected

with the head of the bellows 11 by a stud 20 through the intervention of a cushioning spring connection which affords lost motion at 21. The last-mentioned end of the pivotal lever 17 is also slidably connected to the float spindle 22 by the 5 spring extension 23. 24 is a light cushioning spring for the spring extension 23, and the screw 24a is a means for adjusting the bellows 11. It is evident that, in the normal expanded position of the bellows 11, the float 14 can operate the 10 valve 1, and that when the float 14 is seated in the float chamber 6, the bellows by compression can operate valve 1.

In starting, the float 14 is seated and the valve 1 is opened. High pressure refrigerant passes 15 the valve 1 and with some reduction in pressure reaches the cooling coils which are warm, and rapid evaporation of the refrigerant develops abnormal pressure in the chamber 5 before the 20 cooling coils are full and before liquid reaches the float chamber from the coils, and this pressure acting upon the bellows 11 causes them to close the valve 1, thus excluding high pressure refrigerant from the coils until the abnormally high 25 rate of evaporation in the coils and the consequent high pressure in the chamber 5 are reduced. Thereafter liquid from the cooling coil enters the chamber 6 and the level of this liquid 30 acting on the float 14 causes it to control the valve in the usual manner.

The above-described operations are repeated, as required, to keep the temperature at the desired point.

The described device and its connections replace a thermostatic device often employed in refrigerating apparatus and responsive to the temperature of the low pressure refrigerant, and the bellows or pressure responsive device is less liable to fail in operation, because its operation is not dependent upon a confined body of gas which, in 40 practice, is subject to leakage.

25 is a baffle plate arranged opposite the low pressure refrigerant inlet 8 and it is perforated for the escape of liquid to the float chamber 6. From the float chamber 6 liquid, especially oil 45 or lubricant, flows over the dam 26 into the oil sump 27 from which the lubricant enters the off-take 9 to the compressor by way of the hole 29. Gas enters the offtake 9 at the open upper end thereof. 28 is a baffle plate depending into the 50 oil sump 27.

Between the cold fluid in the chamber 5 and in the sump 27 and the hot refrigerant in the coil 3, heat exchange occurs, which effects economy in operation.

It will be obvious to those skilled in the art to which the invention relates that modifications may be made in details of construction and arrangement and in matters of mere form without departing from the spirit of the invention which is not limited to such matters or otherwise than the prior art and appended claims may require.

I claim:

1. In a refrigerating apparatus the combination of a control valve for high pressure refrigerant, a chamber subdivided into a float chamber and an accumulator chamber and into which low pressure refrigerant is admitted, a float in said float chamber, a bellows externally exposed to the pressure in said chamber and internally to the atmosphere, a pivotal lever to one end of which the control valve is attached, a spring connection between the other end of the lever and the float, and a lost motion spring connection between the last-mentioned end of the lever and the bellows.
2. In a refrigerating apparatus of the type described, the combination of, a chamber into which low pressure refrigerant is delivered and which includes an oil sump portion, a temperature exchange coil in contact with the outside face of the wall of the sump, and connections for leading the high pressure refrigerant through said coil.
3. In a refrigerating apparatus of the type described the combination of, a control valve for the high pressure refrigerant, a bellows for closing said control valve and responsive to the occasional relative high pressure of the low pressure refrigerant, a fluid level responsive device responsive to the level of the low pressure refrigerant for normally regulating and opening and closing said control valve during normal operation of the apparatus, and mechanical connections between said control valve and said bellows and said fluid level responsive device whereby either said bellows or said device may operate said control valve.
4. In a refrigerating apparatus, the combination of, a casing having a chamber therein into which low pressure refrigerant is delivered, said chamber including an oil sump, a temperature exchange coil in heat transfer relation to said oil sump, and connections for leading high pressure refrigerant through said coil.
5. In a refrigerating apparatus, the combina-

tion of, a control valve for high pressure refrigerant, a chamber sub-divided into a float chamber and an accumulator chamber and into which low pressure refrigerant is admitted, a float in said float chamber, a bellows exposed on the outside to the pressure in said chamber and on the inside to the atmosphere, and mechanism interposed between the valve and the float and the bellows whereby the valve is closed by the bellows when the pressure of the low pressure refrigerant is relatively high and opened and closed and controlled by the float when the pressure of the low pressure refrigerant drops.

6. In a refrigerating apparatus of the type described the combination of, a control valve for the high pressure refrigerant, a float device responsive to the level of the low pressure refrigerant for opening and closing and regulating the control valve when the pressure of the low pressure refrigerant is comparatively low and the apparatus is in operation, a pressure-responsive device internally vented to atmospheric pressure and externally exposed to the pressure of the low pressure refrigerant and when the pressure of the low pressure refrigerant is relatively high adapted to close the control valve, and mechanical connections between said valve, the float device and pressure device.

7. In a refrigerating apparatus, the combination of, a casing divided into a float chamber and an accumulator chamber, an offtake for low pressure refrigerant having its inlet adjacent the top of the accumulator chamber, a control valve for high pressure refrigerant, a pressure-responsive device internally vented to the atmosphere and externally exposed to the pressure in the float and accumulator chambers so as to operate in response to relatively high pressure of the low pressure refrigerant to close said valve, a float mounted in the float chamber and responsive to the liquid level of the low pressure refrigerant to open and close and regulate said valve when the pressure of the low pressure refrigerant is relatively low, and lost motion connections between said valve and said float and said pressure-responsive device whereby the float controls said valve and the device occasionally closes it.

HERBERT C. HARVEY.
